UNITED STATES PATENT OFFICE.

LEE O. GILLILAND AND FRANK A. SHARPNECK, OF CHICAGO, ILLINOIS; SAID
SHARPNECK ASSIGNOR TO SAID GILLILAND.

CARBURETER.

1,119,821.

Specification of Letters Patent.

Patented Dec. 8, 1914.

Application filed November 13, 1911. Serial No. 660,022.

To all whom it may concern:

Be it known that we, LEO O. GILLILAND and FRANK A. SHARPNECK, citizens of the United States, both residing at Chicago, in 5 the county of Cook and State of Illinois, have invented certain new and useful Improvements in Carbureters, of which the following is a specification.

Our invention relates to devices for carbureting air and has especial reference to structures of this character for use in conjunction with internal combustion engines whereby to supply the fuel charge for such engines.

15 One of the objects of our invention is to provide a device easily controllable as to the volume of the fuel charge and whereby the hydro-carbon particles may be more thoroughly mingled and more uniformly distributed with and in the necessary air or gas, so as to insure a more even saturation than can be attained by the employment of apparatus ordinarily in use.

Another object of our invention is to provide a reservoir chamber wherein to always retain a mixed primary charge of fuel whereby the associated engine may be more readily and quickly started. And still another object of our invention is to provide a structure whereby the increased velocity of the pistons of the engine will not serve to unduly increase the richness of the charge passing through the carbureter to the end that the engine cylinder will receive 30 an abnormally rich charge at high speed and a sub-normal charge at a relatively low speed. But, by the operation of our improved device it will receive a charge at all times commensurate with its requirements.

40 Other and further objects of our invention will become readily apparent to persons skilled in the art from a consideration of the descriptions hereinafter contained taken in conjunction with the drawings, wherein;

45 Figure 1 is a central vertical section of the device as connected to a main manifold of an internal combustion engine; Fig. 2 is a plan view of the same looking from below; Fig. 3 is a transverse section taken on lines 50 3-3 of Fig. 1, looking with the arrows; Fig. 4 is a side elevation; Fig. 5 is a vertical section of a portion of the device taken at a right angle from the section shown in Fig. 1; Fig. 6 is a section taken on line 6-6 of

Fig. 1; Fig. 7 is an isometric view of the air controlling shutters.

In all of the views the same reference characters indicate similar parts.

The casing 10 contains two chambers, a fluid, or gasoline chamber 11 and a mixing chamber 12. A separable auxiliary casing 13 may be attached to the casing 10 and contains a fuel chamber, or mixture reservoir 14. The carbureter may be used without this casing or the casing may be used 65 with other carbureters and perform the same functions which it is designed to perform in connection with this carbureter.

In the embodiment shown the casing 13 is secured to the casing 10 by means of screws 70 15 and 16, and the device, as a whole, is secured to the manifold 17 by screws 18 and 19. A fluid fuel inlet pipe 20 is secured to a threaded boss 21 projecting from the casing 75 inclosing the float chamber, by means of a nut 22, as usual in such structures. A float 23, which may be of cork or a hermetically sealed hollow metallic body, as usual, is provided with a depending valve stem 24 to the end of which a valve 25 is connected. 80 The valve is free to move in a chamber 26 provided in the hollow boss 21. When the fluid within the chamber 11 reaches the predetermined height the float raises the valve 25 and closes the port which controls communication between the pipe 20 and the chamber 11, thereby shutting off the supply 85 of gasoline. The conduit 27 establishes communication between the chamber 11 and the nozzle 28, and between the outlet of the nozzle and the said chamber 11 there is a valve 29 having a rounded end as at 30 which opens or closes communication between the chamber 11 and the outlet of the nozzle when the valve stem 31 is rotated. 90 The valve stem 31 is screw-threaded, as at 32, into an exteriorly screw-threaded, hollow boss 33. A packing gland 34 is screw threaded on to the boss 33 and serves the purpose of preventing leakage of the fluid 100 by encompassing the necessary packing to render the joint substantially fluid-tight. When the valve stem 31 is rotated it causes the valve 30 to approach, or to recede from the terminal port of the vertical perforation 105 35 in the nozzle, and thereby closes the opening in the nozzle to a greater or less extent according to the separation of the valve

30 and coating port. The opening 35 of the nozzle 28 is flanked by two transverse bores, as at 36 and 37. The lower end of the valve stem 31 is screw threaded as at 37 and on the screw threaded end are nuts 38 and 39 that may be moved freely along the threaded stem to any selected position. Between these nuts, and surrounding the stem is a lever 40 that may be clamped between the nuts at any position desired along the threaded length of the stem. When this lever 40 is rotated through a given arc the valve 30 is opened or closed to a greater or less extent in accordance with the extent to which the lever 40 is moved. The means for controlling the air to be admitted to the mixing chamber of the device is also employed for moving the lever 40 to control the admission of gasoline into said mixing chamber, proportionately as the air admitted therein is controlled by the same instrumentality.

To the lower end of the casing, inclosing the mixing chamber 12, are hinged four angular air-valve shutters 41, each shutter carrying a hinged member 42 for cooperation with the hinge members 43 and 44 contained on the casing. When the four shutters occupy positions in the same horizontal plane, as shown in Fig. 1, the air opening into the mixing chamber 12 is substantially closed by the four shutters, and when these shutters are raised as in the act of providing an opening for the admission of air into the mixing chamber the extent of the opening increases as the shutters are raised, thereby extending the opening radially farther from the nozzle 28 as the area of the opening increases.

We will now describe the means for raising the shutters and thereby providing larger and variable openings for the admission of air and simultaneously increasing the flow of gasoline through the nozzle commensurate with the increased volume of the air admitted into the mixing chamber of the device. A stem 45 depends from the bottom of the casing 10 and is surrounded by a sleeve 46 which is movable freely in a vertical direction thereon. To one side of the sleeve 46 is a boss 47 which carries a stud or screw 48. A controlling lever 49 is pivoted, as at 50, and is provided with arms 51 and 52. The arm 51 is slotted, as at 53, for engagement with the stud 48, so that when the arm 51 is raised the slot 53 will permit free relative movement between the stud 48 and the arm 51 thereby to raise the sleeve 46. Projecting laterally from the sleeve 46 is a bracket 55, carrying on its outer end a ring 56, which ring is substantially concentric with the axis of the mixing chamber 12. The ring 56 carries four hinge members 57, which are substantially of the same character as the hinge members 58 carried by

each of the shutters 41. Links 59 are included between the hinge members 57 and 58 and are pivoted thereto by appropriate pins, so that when the ring 56 is lifted the motion is independently conveyed to each of the shutters 41 as clearly apparent from the drawings. In Fig. 5 the position of the valve shutters 41 is shown in full lines, the position which they occupy when the air-admission opening to the mixing chamber is closed, and they are also shown in dotted lines in the positions which they occupy when the air-admission port is thereby fully opened. By means of the controlling lever 49 the air admission shutters 41 may be made to occupy any desired intermediate position, and simultaneously with air regulating valve the gasoline controlling valve 30 is rotated and thereby the quantity of gasoline permitted to flow through the nozzle 28 is correspondingly varied. The lever arm 52 is connected to the arm 40 of the gasoline valve by means of a link 60, whereby the movement of the controlling valve handle 49 is transmitted to the shaft 31 of the gasoline controlling valve 30. The relation of the gasoline port opening to the opening of the air valve may be varied by moving the nuts 38 and 39 up or down on the stem 31, and clamping the lever 40 at any desired selected position, so that when the air valves are completely closed the gasoline valve may be closed to any desired extent. The casing 10 is perforated as at 62 and the perforation is covered by several layers of wire cloth disks 63. A spacing ring 64 is then placed in the reservoir chamber 14 for support of another pack of wire cloth disks 65, thereby providing an intermediate chamber 14 within which may be contained a mixed charge of gasoline and air fuel for the engine.

The lower bunch of wire cloth disks provides an impediment to the flow of the air and gasoline through the chamber 14 whereby greater or more intimate mixture is attained in the mixing chamber. The pack of wire cloth also serves as a means of breaking up into finer particles the fluid gasoline taken through the nozzle 28. The pack 65 serves as a means for further mixing the charge before it enters the engine, as in the case where the charge has remained in the chamber 14 for some time. The action of the reticulated material tends to produce a more intimate mixture of the liquid and fluid, or vapor and air, thereby delivering to the engine a more completely combustible charge than otherwise, and the same means tends to retain the mixed charge within the chamber 14 after the engine has ceased operation, ready to be taken into the engine upon the first turn of the crank in the process of starting. The perforations 36 and 37 are made transverse of the vertical perfora-

tion 35 of the nozzle 28 because when the shutters 31 are raised the air striking under the bottom surface of the shutter is deflected at an angle to the vertical plane from each 5 shutter across the upward surface of the nozzle and caused to sweep over the transverse perforations 36-37 on the opposite side of the respective shutter, thereby producing a more direct entraining effect over 10 the gasoline nozzle. This effect is produced to a greater extent by the air that passes directly over the apex end of the shutter. The end of the valve 30 is made round instead of a needle point so that a smaller 15 vertical movement of the valve stem 31 will effect a proportionately larger opening into the aperture 35 of the nozzle. This we find to be more practical than to increase the pitch of the screw thread 32.

20 While we have herein shown a specific embodiment of our invention it is apparent, to persons skilled in the art, that many changes may be made in the structure within the scope of the claims without departing 25 from the spirit of the invention.

Having described our invention what we claim is:

1. In a device of the character described, a casing containing a carbureting chamber, 30 a nozzle projecting thereinto, a casing containing a chamber for fuel supply, said latter chamber communicating with said nozzle, a valve controlling said fuel supply to said nozzle, a valve comprising a plurality 35 of vertically movable, radially opening shutters controlling the air supply and when open lying in planes to direct air against the nozzle openings and a handle for coincidentally moving said valves.
- 40 2. In a device of the character described, a casing containing a carbureting chamber, a fuel nozzle located centrally thereof projecting thereinto, a valve controlling said

nozzle, an air valve for closing said chamber comprising a plurality of shutters 45 hinged to the sides of the casing and closing by movement toward said nozzle, and when open lying in planes to direct air against the nozzle openings, and means for coincidentally moving said shutters and said 50 fuel controlling valve.

3. In a device of the character described, a casing containing a carbureting chamber, a fuel nozzle located centrally thereof projecting thereinto, a valve controlling said 55 nozzle, an air valve comprising a plurality of shutters surrounding said nozzle hinged to the sides of the casing and closed by movement toward said nozzle, a threaded stem for said nozzle valve, means to turn 60 said stem for operation of said nozzle valve, a ring surrounding said stem having connection to said shutters, and connections between said ring and the nozzle-operating 65 means for movement of said nozzle and shutters in harmony.

4. In a device of the character described, having a nozzle and a plurality of air-controlling shutters surrounding said nozzle, rotary means for controlling said nozzle, 70 vertically moving means for controlling said shutters surrounding said rotary nozzle-controlling means, one of said means being adjustably connected with a movable operating member, and a movable operating 75 member for effecting operation of said nozzle and shutters through the agency of said rotary and vertically movable means.

In testimony whereof we hereunto set our hands.

LEE O. GILLILAND.
FRANK A. SHARPNECK.
